CHARLES DOUGLIS, OF LAWRENCE, NEW YORK

CONNECTER DEVICE FOR CUFFS OF KNICKERS

Application filed October 16, 1929. Serial No. 400,046.

The present invention has in view the provision of a connecter unit which is adapted to engage the open ends of the cuff or leg band of knickers and the like for tightening the same about the leg of the wearer. The connecter unit is longitudinally adjustable to vary the distance between the points of attachment with the cuff or leg band and is elastic so that it will give with the movement of the leg muscles of the wearer. Heretofore, knickers and the like have been provided with a strap extension forming a part of the cuff or band which is adapted to engage a buckle to draw the band tightly about the leg of the wearer. Such arrangement provides a rigid construction which binds the leg and retards circulation. In order to avoid the discomfort caused by such rigid and inflexible leg band heretofore used in garments of this nature, the present invention seeks to provide a connecter unit which is longitudinally adjustable to vary the length between its points of engagement with the cuff and which is elastic and will give with the movement of the leg muscles of the wearer.

Still other objects reside in the novel features of construction and arrangement of parts which will be described and claimed hereinafter.

The invention is shown in the accompanying drawing in which

Figure 1 is a longitudinal sectional view of the connecter unit embodying the invention and

Figure 2 is a view showing the connecter in applied position.

The connecter 10 shown in the drawings illustrating the invention is adapted to connect the open ends of a cuff or leg band 11 formed at the bottom of short length trousers, such as knickers, golf trousers and the like. The open ends of the cuff or leg band 11 are provided with attaching means for connecting the connecter unit 10 therebetween. As shown in Figure 1 of the drawing, one end of the cuff or band 11 is provided with a button 12 which is adapted to engage a button hole 13 in a tab 29 secured to one end of the elastic member 24. This elastic member is

provided with snap fasteners 25 which form a loop 26 in the said elastic member when the fasteners are together. The loop 26 engages a bar of a link member 27 carried by the other end of the open cuff or band 11. The opposite end of the elastic member 24 is looped through a link 28 secured to the said tab 29. The end 30 of the elastic member 24 is attached to the middle bar of a link 31 which is slidably mounted on the elastic member 24. The said link 31 may be moved longitudinally on the member 24 to shorten or lengthen the connecter. Constructed in this manner the connecter 10 may be readily unbuttoned from the button 12 on one end and released from the link 27 at the other so that it can be removed when it is necessary to cleanse the garment.

It is understood that the said connecter is constructed so that it may be applied to the bottom of the leg members of short trousers, such as knickers and the like, to hold the trousers in position below the knee and which is made elastic so that it will give with the movement of the leg muscles of the wearer and may be adjusted longitudinally to fit the wearer so that it will not bind the leg.

I claim:

In combination, a garment provided with a cuff having free ends, one end of which is provided with a link member, an attaching element carried by the opposite cuff end, a connecting device for connecting the ends of said cuff, the said connecting device comprising an end member engageable with the attaching element carried by the one cuff end, a link connected to said end member, an elastic member having one end looped through the last mentioned link, an adjustable element secured to the free end of said loop and mounted to slide on the said elastic member to vary the length of the said loop, a looped member secured to the opposite end of said elastic member and engaging the link carried by the one cuff end and detachable connecting means carried by the last mentioned looped member for holding the loop in closed position.

CHAS. DOUGLIS.
